MEANS FOR ACTUATING THE DOOR LOCKS OF MOTORCARS

John H. Orr, Coventry, England, assignor to Car-
bodies Limited, Coventry, England

Application December 1, 1950, Serial No. 198,638

Claims priority, application Great Britain
December 17, 1949

4 Claims. (Cl. 292—336.3)

1

The door locks of many modern motor-cars are arranged to be actuated by a push-button on the outer side of the door, there being a loop-handle, or some equivalent hand-grip by which the door, when the latch has been released, can be pulled open. The object of the invention is to provide a means of operating the latch mechanism whereby a loop-handle, or other projecting hand-grip can be dispensed with, thus improving the appearance of the car and minimising excrescences on its outer surface.

According to the invention, the latch mechanism, for a motor-car door having a waist rail, is connected to be operated from a member which, when the latch is shot, is substantially continuous with the upper surface of the waist rail and which, for retracting the latch, is manually depressible, against a biasing means, into a housing within the waist rail, an edge of the housing, when the member is depressed, providing a hand-hold by the use of which the door can be opened.

Conveniently the said operating member is a plunger which is rectangular in plan and is recessed into a housing in the top of the waist rail, the plunger being for acting on the top of a substantially-vertically reciprocable thrust member operatively connected to the latch mechanism. The biasing means for holding the plunger to be flush with the waist rail can either be a spring of the lock mechanism or an additional spring reacting between the bottom of the recess and the under surface of the plunger.

Alternatively the operating member could be hinged (e. g., at its outer edge) to the waist rail and have the side opposite the hinge for acting on the thrust member.

Whilst not limited in this respect, the operating means of the invention is particularly adapted for operating a car door latch mechanism of the kind according to specification Serial No. 200,159, filed December 11, 1950.

Obviously a key-operated, or other suitable lock could be arranged to prevent unauthorised opening of the door, the lock, for example, being for coaction with the thrust member.

When installing the actuating means in a motor-car door, it is desirable to avoid the necessity for positioning the latch-operating member (which is fast with the door) extremely accurately with respect to the remaining portions of the latch mechanism. Also, when the latch-operating member is a plunger, and a coacting thrust member which is connected to the latch mechanism has a swinging movement in operation, relative lateral movement between the plunger and top of the thrust member must be provided so as to avoid binding of the plunger in its housing.

According to a further feature, therefore, the operating member acts on the thrust member

2

through means permitting of their relative lateral displacement from the line of thrust.

In the drawings:

Figure 1 is a perspective view of a portion of a motor-car door provided with one form of latch actuating mechanism according to the invention;

Figure 2 is a cross-section, on the line 2—2 of Figure 1 and drawn to a larger scale;

Figure 3 is a cross-section on the line 3—3 of Figure 2; and

Figure 4 is a view similar to Figure 3, but showing a modified construction.

Referring to the drawings the motor-car door 11 has, in the waist rail portion 12, a rectangular recess 13 beneath which is secured, as by welding, a housing 14 of corresponding cross-section. Within the housing is a plunger 15 having, in two opposite faces, blind grooves 16 which are engaged by pins 17 fast with the housing for limiting the movement of the plunger. So that the plunger can move freely within the housing the former can be provided with spring-pressed anti-friction balls 18 making rolling contact with the inner wall of the housing.

Within the free edge 19 of the door is mortised the casing 20 of a latch mechanism, a projecting operative end 21 of the latch lever extending through a slot 22 of the casing.

The plunger 15, on being manually depressed is for operating, through a thrust member 23, the latch mechanism for raising the protruding end 21 of the latch.

In Figure 3 the thrust member is shown provided with a laterally extending platform 24 at the head, the platform having secured thereto on each side of the line of thrust a ball-cup 25. The plunger has fast therewith two depending stems 26 with coacting ball-cups 27 at the feet. An anti-friction ball 28 is enclosed between each pair of cups 25, 27, and the depths of the cups (which latter have flat bottoms) is such that the balls 28 keep them out of contact with each other, the internal diameters of the cups being considerably greater than the diameter of the balls. The platform and plunger can be interconnected by a tension spring, not shown, but that would not be necessary in instances where the thrust member is spring-biased in the upward direction. It will be seen that, due to the balls 28, the plunger could effectively operate the thrust member 23 when in a variety of laterally displaced relative positions, thus avoiding any necessity for those two parts to be accurately aligned during assembling of the latch mechanism to the door.

In the construction of Figure 4, which is simpler than that of Figure 3, the plunger is interconnected with the platform 24a, by a pair of rubber thrust stems 26a of which the ends are suitably anchored to the two parts. Thus the

upper ends of the stems can be bonded in bores 29 in the plunger, and the lower ends can be bonded in brackets 30 suitably secured to the platform 24a.

When it is desired to open the car door from the outside, the operator has only to depress the member 15, using, perhaps, two fingers, and this not only releases the latch but, the fingers automatically engaging the outer edge 31 of the recess disclosed, enables the door to be pulled open directly.

What I claim as my invention and desire to secure by Letters Patent of the United States is:

1. Operating means, for a latch mechanism of a motor-car door having a waist rail, comprising an operating plunger within an opening in the waist rail, an open-ended housing fast with said waist rail and having one open end registering with said opening, said housing being for said plunger, means acting between said housing and plunger for limiting movement of the latter from a position in which the plunger head is substantially continuous with the waist rail when the latch-bolt is in latched position, to a depressed position inwardly of the adjacent open end of said housing, a reciprocable member adjacent and substantially aligned with the other open end of said housing and operatively connected to said latch mechanism, two laterally-spaced pairs of facing cups with flat internal bottoms secured in juxtaposition to said plunger and member, and a thrust ball of less diameter than said bottoms interposed between the facing cups of each pair and separating the rims thereof whereby said member can be moved by a full depression of said plunger to move said latch-bolt to a non-latched position, an edge of said opening when said plunger is thus depressed providing a hand-hold by the use of which the door can be opened, and said thrust balls by being movable laterally in their coacting cups permitting relative lateral deviation of said plunger and member from the line of thrust.

2. Operating means, for a latch mechanism of a motor-car door having a waist rail, comprising an operating member housed in an opening in the waist rail and having its head substantially continuous therewith in the latched position of the latch-bolt, a reciprocable member operatively connected to said latch-mechanism and substantially aligned with said operating member, a laterally-extending platform fast with that end of said reciprocable member which is adjacent said operating member, a pair of parallel thrust-transmitting means extending between said operating member and said platform, said thrust-transmitting means acting on said platform with their lines of thrust substantially parallelly on opposite sides of the line of thrust of said reciprocable member whereby, when said operating member is depressed in its housing, said thrust-transmitting means deliver a balanced thrust to said reciprocable member to move said latch-bolt to the non-latched position, an edge of said opening when said operating member is thus depressed providing a hand-hold by the use of which the door can be opened, and the opposite ends of said thrust-transmitting means being relatively laterally displaceable to compensate for any relative lateral deviation of said operating and reciprocable member from the line of thrust.

3. Operating means, for a latch mechanism of a motor-car door having a waist rail, comprising an operating plunger within an opening in the waist

75

rail, an open-ended housing fast with said waist rail and having one open end registering with said opening, said housing being for said plunger, means acting between said housing and plunger for limiting movement of the latter from a position in which the plunger head is substantially continuous with the waist rail when the latch-bolt is in latched position, to a depressed position inwardly of said one open end of said housing, a reciprocable member operatively connected to said latch mechanism and substantially aligned with the other open end of said housing, a laterally-extending platform fast with that end of said reciprocable member which is adjacent said plunger, a pair of parallel thrust-transmitting means extending between said plunger and said platform, said thrust-transmitting means acting on said platform with their lines of thrust substantially parallelly on opposite sides of the line of thrust of said reciprocable member whereby, when said plunger is depressed in its housing, said thrust-transmitting means deliver a balanced thrust to said reciprocable member to move said latch-bolt to the non-latched position, an edge of said opening when said plunger is thus depressed providing a hand-hold by the use of which the door can be opened, and the opposite ends of said thrust-transmitting means being relatively laterally displaceable to compensate for any relative lateral deviation of said plunger and reciprocable member from the line of thrust.

4. Operating means, for a latch mechanism of a motor-car door having a waist rail, comprising an operating plunger within an opening in the waist rail, an open-ended housing fast with said waist rail and having one open end registering with said opening, said housing being for said plunger, means acting between said housing and plunger for limiting movement of the latter from a position in which the plunger head is substantially continuous with the waist rail when the latch-bolt is in latched position, to a depressed position inwardly of said one open end of said housing, a reciprocable member operatively connected to said latch mechanism and substantially aligned with the other open end of said housing, a laterally-extending platform fast with that end of the said reciprocable member which is adjacent said plunger, a pair of parallel laterally-spaced rubber thrust rods interconnecting said plunger and said platform, said thrust rods acting on said platform with their lines of thrust substantially parallelly on opposite sides of the line of thrust of said reciprocable member whereby, when said plunger is depressed in its housing said thrust rods deliver a balanced thrust to said reciprocable member to move said latch-bolt to the non-latched position, an edge of said opening when said plunger is thus depressed providing a hand-hold by the use of which the door can be opened, and the lateral resiliency of said thrust rods permitting them to be deflected from the straight when said plunger and reciprocable member are not strictly aligned.
